UNITED STATES PATENT OFFICE.

LELAND E. PECK, OF WYOMING, IOWA.

PRESS.

Application filed March 25, 1921, Serial No. 455,471. Renewed April 21, 1923.

To all whom it may concern:

Be it known that I, LELAND E. PECK, a citizen of the United States, residing at Wyoming, in the county of Jones and State 5 of Iowa, have invented new and useful Improvements in Presses, of which the following is a specification.

This invention relates to metal working machines and has especial relation to presses 10 designed for punching, cutting and similar operations.

An object of the present invention is the provision of a press as above stated, which is provided with a table capable of a wide 15 range of adjustment, the operating mechanism providing for rapid and easy method of operation.

Another object is the provision of a press having an accurate and effective feeding 20 mechanism which will supply a maximum amount of power for feeding with a minimum of effort on the part of the operator.

With the above and other objects in view, the invention further includes the following 25 novel features and details of construction, to be hereinafter more fully described, illustrated in the accompanying drawings and pointed out in the appended claims.

In the drawings:

30 Figure 1 is a front elevation of a press embodying the present invention.

Figure 2 is an edge view of the same.

Figure 3 is a section on the line 3—3 of 35 Figure 1.

Figure 4 is a similar view on the line 4—4 of Figure 1.

Figure 5 is a vertical section on the line 5—5 of Figure 1.

Figure 6 is a similar view on the line 6—6 40 of Figure 1.

Referring in detail to the drawings, wherein like characters of reference denote corresponding parts, the reference character 10 indicates the base of the press frame 45 which is preferably formed of channel iron and from which rises channeled side members 11, the latter being connected at their upper ends by means of a channel beam 12 to provide a substantially rectangular vertical frame. This frame is supported in an upright position by means of horizontally arranged bars 13 which are connected to the side members 11 by braces 14. Also connecting the side members 11 and spaced from the 50 channel bar 12, is a channel beam 15, which is provided near each end with vertically

disposed bearings 16. The bearings 16 receive one end of vertically disposed shafts 18, whose opposite lower ends are mounted in bearings 19 secured to the base 10. 60

The shafts 18 are threaded throughout a greater portion of their lengths and mounted for movement longitudinally of these shafts is a table 20, which is preferably constructed of two channel iron bars 21 arranged side by side and carrying at each end internally threaded sleeves or nuts 22. These sleeves or nuts 22 are secured to the table as indicated at 23 and extending from the outer sides of the said sleeves or nuts diametrically 70 opposite the table 20 are projections 24, which engage and slide freely on the side members 11. The nuts or sleeves 22 are secured to the table 20 and the extensions 24, as indicated at 25. 75

The rotation of the shafts 18 will, through their engagement with the sleeves or nuts 22, move the table vertically, the direction of movements being controlled by the direction of rotation of the shafts. In order to rotate 80 these shafts there is secured to their upper ends a gear 26, which is engaged and driven from a worm 27, mounted upon a shaft 28, one of these worms being provided for each of the gears 26 so that the shafts 18 will be 85 simultaneously rotated. The shaft 28 is mounted in suitable bearings carried by the side members 11 and extends beyond one of said members, where it is provided with a hand wheel 29. The threads of the shafts 90 18 are preferably of a right hand pitch.

Mounted in a bearing 30 which is secured to the beams 12 and 15, is a vertically disposed shaft 31, the upper portion of which is formed with a longitudinally disposed key way 32, which is engaged by a key 33 extending from the upper end of the bearing 30. The shaft 31 is formed for a portion of its length with a left hand thread 34 and mounted upon the threaded portion of the shaft is a sleeve or nut 35. The upper end of this sleeve is swiveled in a bracket or bearing 36, which is secured to the under edge of the beam 15 as shown at 37 and located within this bracket or bearing 35 are 100 antifriction devices 38.

Secured to the sleeve or nut 35 is a hand wheel 39, the latter having in turn secured thereto, a ring gear 40. This ring gear is engaged by a pinion 41 secured to one end 110 of a shaft 42, the said shaft being mounted in bearings 43 depending from the lower

edge of the beam 15. In addition, the shaft 42 is provided at its outer end with a gear 43', which is engaged by a pinion 44, secured upon the inner end of a counter shaft 45. This last mentioned shaft is mounted in suitable bearings 46 which are carried by the frame of the machine and extends beyond one of the side members 11 and has secured thereon a hand wheel 47. Also 10 mounted upon the shaft 45 is a ratchet wheel 48, the teeth of which are engaged by a spring actuated dog 49 carried by a hand lever 50. This lever is mounted for swinging movement upon the shaft 45 and 15 its latch is controlled by a hand lever 51.

Key 38 prevents shaft 31 from turning with nut 35, when the latter is turned around in the bracket 36, thereby enabling the threads of the nut to exert a thrust vertically of the shaft for sliding the same up or down thru guide-bearing 30. The shaft 31 may thus be vertically reciprocated through the medium of either the hand lever 50 or the hand wheel 47, the latter 25 increasing the power applied to the shaft through the medium of the gears 43' and 44. This power may be further increased by operating the lever 50, the increased leverage supplied, increasing the power applied to the shaft 31, as will be readily understood.

The invention is susceptible of various changes in its form, proportions and minor details of construction and the right is herein reserved to make such changes as properly fall within the scope of the appended claims.

Having described the invention what is claimed is:—

40 1. A device of the character described comprising a vertical frame presenting a work-table at its lower portion and a vertically disposed internally threaded bearing at its upper end and overlying the said

table, a gear swiveled in a bracket at the 45 lower end of the bearing and presenting a threaded bore in line with the bearing, a tool-holder threadedly engaging the said bearing and the threaded bore of the said gear, a shaft journaled in bearings horizontally of the said frame, a pinion on one 50 end of the shaft engaging the said gear, and means at the other end of the said shaft for rotating the shaft.

2. A device of the character described 55 comprising a frame having an internally threaded vertically disposed bearing at its upper end, a work-table mounted on the frame below the said bearing, a gear swiveled in a bracket at the lower end of the 60 bearing and presenting a threaded bore in line therewith, a tool-holder extending through the said bearing and the threaded bore of the said gear, and being threadedly engaged with each, forwardly and rearwardly arranged shafts journaled horizontally 65 in bearings on the said frame and in spaced parallel relation to each other, a pinion on the forwardly arranged shaft engaging the said gear, means on the rearwardly arranged shaft for imparting rotation thereto, and gearing between adjacent ends of the said shafts.

3. A device of the character described 70 comprising a vertical frame having a vertically disposed bearing at its upper end, a vertically adjustable work-table mounted on the frame below the said bearing, a gear 75 swiveled in a bracket at the lower end of the said bearing and presenting a threaded bore in line with the bearing, a tool-holder extending through the said bearing and the said bore and threadedly engaging the latter, and means for imparting rotation to the said gear including a shaft and a ratchet 80 mechanism for turning the shaft.

In testimony whereof I affix my signature.

LELAND E. PECK.
